UNITED STATES PATENT OFFICE.

HENRY A. WEIHLMAN, OF PHILADELPHIA, PENNSYLVANIA, ASSIGNOR TO JOHN F. SIMONS AND THOMAS MADDOCK, OF SAME PLACE, FREDERIC M. SIMONS, OF SWARTHMORE, PENNSYLVANIA, AND EDWARD S. SIMONS, OF ORANGE, NEW JERSEY.

DESIGN FOR A BACK FOR BRUSHES.

SPECIFICATION forming part of Design No. 27,166, dated June 8, 1897.

Application filed April 24, 1897. Serial No. 633,804. Term of patent 7 years.

To all whom it may concern:

Be it known that I, HENRY A. WEIHLMAN, of the city and county of Philadelphia, State of Pennsylvania, have invented a new and original Design for Backs for Brushes and Similar Articles, of which the following is a specification.

My design is illustrated in the accompanying drawings, in which—

10 Figure 1 is a plan view of the back of a brush or hand-mirror having my design applied; and Fig. 2 is a similar view, omitting the handle of the brush or mirror.

15 A is the back of the body of the brush or mirror, and B is the handle. In some cases the handle B is omitted, as in clothes-brushes and "military" hair-brushes, as is shown in Fig. 2.

20 The design upon the body A consists of the ornamental border shown, composed of the representation of roses *a* and the intermediate ornamental scrolls *b*. The central portion *c* is plain or unornamented.

The design upon the handle B consists of the rose-patterns *a'* and ornamented scrolls *b'*, arranged as shown and leaving a plain or unornamented space *c'* inclosed by the ornamentation.

What I claim as new, and desire to secure by Letters Patent, is—

30 1. The design for the back of a brush or similar article composed of the body A and handle B substantially as herein shown and described.

2. In a design for the back of a brush or similar article the body A, substantially as herein shown and described.

35 3. In a design for the back of a brush or similar article, the handle B substantially as herein shown and described.

40 In testimony of which invention I hereunto set my hand.

HENRY A. WEIHLMAN.
